WINDING-MACHINE.

1,123,256.

Specification of Letters Patent.

Patented Jan. 5, 1915.

Application filed May 6, 1907. Serial No. 372,153.

To all whom it may concern:

Be it known that I, ROGER D. DE WOLF, a citizen of the United States, and a resident of Pittsburgh, in the county of Allegheny and State of Pennsylvania, have invented a new and useful Improvement in Winding-Machines; of which the following is a specification.

My invention relates to machines for winding wire and other filaments, and it has for its object to provide a machine whereby the winding of very fine wire or other filament may be effected at a rapid rate without breaking or injuring the same.

In transferring very fine wire from a reel or bobbin to a mold or other device, considerable difficulty has generally been experienced in applying uniform tension thereto and in thus causing it to wind smoothly and without breaking, especially when the mold is of rectangular or irregular form. The present invention insures the application of a uniform tension to the wire under all conditions, and if, for any reason, the tension exceeds or falls below predetermined values the winding operation is interrupted.

The single figure of the accompanying drawing illustrates a machine embodying my invention.

A mold or bobbin 1, or any other device upon which it is desired to wind a wire 2, is rotated by a two-part shaft 3 that is operated by means of a pulley 4 and a belt 5. A clutch, comprising members 6 and 7, carried, respectively, by the parts of the shaft, serves to connect and disconnect the said parts, the member 7 being adjustable axially and being normally held in engagement with the member 6 by means of a helical compression spring 8 interposed between the member 7 and a flange or collar 9 upon the shaft. The wire 2 is unwound from a supply reel 10, at substantially the same rate as it is wound upon the mold or bobbin 1, by means of an operative connection between the shaft 3 and the shaft 11 upon which the supply reel 10 is carried, the operative connection comprising disks 12 and 13 that are mounted, respectively, upon the shafts 11 and 3 and corresponding wheels 14 and 15 that make frictional engagement with the disks and are mounted, respectively, upon the extremities of a shaft 16. The friction wheel 15 is so keyed to the shaft 16 that it may be adjusted longitudinally by

means of a position-controlling lever 17 in order to vary the relative rate of rotation of the shafts 3 and 11.

Between the mold 1 and the reel 10 the wire 2 passes over two pulleys 18 and 19, and riding upon the wire between the said pulleys is a third pulley 20 that is carried at the extremity of a pivoted and suitably weighted arm 21. The pulley 20 and the arm 21 form an actuating or governing member for a stop motion device which is arranged as follows: The arm 21 is limited in its movement by stops 22 and 23 that are connected to one terminal of a magnet winding 24, the other terminal of which is connected, through a battery 25, to the arm 21. Thus, when the arm 21 engages the one or the other of the stops 22 and 23 a circuit is established through the winding 24 which thereupon becomes energized and actuates a lever 26 so as to move the clutch member 7 out of engagement with the member 6, the winding operation being, in this manner, interrupted.

In the operation of the machine, the position of the friction wheel 15, with reference to the axis of the disk 13, is adjusted so that the wire 2 is unwound from the reel 10 at the same rate as it is wound upon the mold or bobbin 1, the lever 21, under such conditions, assuming a substantially stationary position between the stops 22 and 23 if the mold 1 is round, and making a vibratory movement if the mold is rectangular or irregular in shape, the tension upon the wire remaining substantially constant. As the diameter of the winding upon the mold or bobbin 1 increases and that upon the reel 10 decreases, the lever 21 will be gradually raised, because the wire is being wound upon the mold or bobbin 1 at a greater linear rate than it is unwound from the reel 10 which causes a taking up of the slack wire, *i. e.*, a shortening of the wire between the pulleys 18 and 19. If the winding is continued in this manner for a sufficient period of time without adjusting the position of the friction wheel 15, the lever 21 will be moved into engagement with the stop 22, whereupon the magnet winding 24 will become energized and effect separation of the clutch members 6 and 7 with consequent interruption of the winding operation. If, for any reason, the wire is unwound from the reel 10 at a greater linear rate than it is wound

upon the mold or bobbin 1, the lever 21 will be lowered, because the length of wire between the pulleys 18 and 19 will increase, and if this condition prevails for a sufficient period of time, the lever 21 will engage the stop 23, whereupon the magnet winding 24 becomes energized and effects separation of the clutch members 6 and 7, thereby interrupting the winding operation. The same result will occur, of course, if the wire breaks between the reel and the mold. Thus it is seen since a constant weight is applied to the portion of the wire between the pulleys 18 and 19, the tension upon the wire remains substantially uniform, and if the length of the wire between the pulleys 18 and 19 is decreased to such an extent that there is danger of breaking the wire, the winding operation is stopped. Likewise, if the length of the wire between the pulleys 18 and 19 increases to a predetermined value interruption of the winding operation is also effected. If, owing to an imperfection in the winding upon the mold or bobbin 1, or for other reason, it becomes necessary to unwind some of the wire therefrom preparatory to rewinding, it is only necessary to reverse the direction of rotation of the shaft 3 and the wire will be wound upon the reel 10 substantially as it is wound upon the mold or bobbin in the forward operation of the machine. The tension upon the wire may be varied by adjusting the weight of the arm 21.

It will, of course, be understood that the arrangement and structural details of the parts here shown may be considerably modified without departing from the spirit of the invention. For instance, a great variety of operative means may be employed for so connecting the mold or bobbin and the supply reel that the wire shall be drawn from the reel at substantially the same rate as it is applied to the mold or bobbin, and many

other suitable means may be employed for interrupting the winding operation when the length of the wire between the pulleys 18 and 19 is not within predetermined limits.

I claim as my invention:

1. In a winding machine for wire and similar filaments, the combination with a bobbin, a supply reel, and an operative connection between the bobbin and the supply reel whereby the supply reel is caused to deliver the wire or filament at substantially the same rate as it is applied to the bobbin, of two guides over which the wire or filament runs between the reel and the bobbin, a member that rides upon the wire or filament between the said guides, and means governed by said member for interrupting the winding operation when the length of wire between the guides is not within predetermined limiting values.

2. In a winding machine for wire and similar filaments, the combination with a bobbin, a supply reel, and an operative connection between the bobbin and the supply reel whereby the supply reel is caused to deliver the wire or filament at substantially the same rate as it is applied to the bobbin, of two guides over which the wire or filament runs between the reel and the bobbin, a member that rides upon the wire or filament between the said guides, and electrical means governed by said member for interrupting the winding operation when the length of wire between the guides is not within predetermined limiting values.

In testimony whereof, I have hereunto subscribed my name this 30th day of April, 1907.

ROGER D. DE WOLF.
